BRIDE DOLL

Edna M. Enfield, R.R. 1, Garber, Okla. 73738

Filed June 21, 1971, Ser. No. 155,388

Term of patent 14 years

Int. Cl. D21—01

U.S. Cl. D34—4 R

FIG. 1 is a perspective view of the bride doll of the present invention;

FIG. 2 is a top view of the bride doll of FIG. 1; and
FIG. 3 is a bottom view of the bride doll of FIG. 1.

I claim:

The ornamental design for a bride doll, substantially as shown.
